UNITED STATES PATENT OFFICE.

JOHN F. RAWLINGS, OF BLOOMFIELD, IOWA.

DESIGN FOR A WATCH-CHARM AND CIGAR-CUTTER.

SPECIFICATION forming part of Design No. 33,848, dated January 8, 1901.

Application filed December 1, 1900. Serial No. 38,377. Term of patent 14 years.

To all whom it may concern:

Be it known that I, JOHN F. RAWLINGS, a citizen of the United States, and a resident of Bloomfield, in the county of Davis and State 5 of Iowa, have invented and produced a new and original Design for a Watch-Charms and Cigar-Cutter, of which the following is a specification.

Reference is to be had to the accompanying 10 drawings, forming a part of this specification, in which similar characters of reference indicate corresponding parts in both views.

Figure 1 is a perspective view of a watch-charm and cigar-cutter embodying my design, 15 and Fig. 2 is a longitudinal section of the same.

The design presents two essentially semi-bell-shaped side members *a* of concavo-convex cross-sectional form. These side mem-

bers *a* present at their upper extremities a crossing or bridge-piece *b*, surmounted by an 20 element *c* of annular configuration.

The design further presents the appearance on the side members *a* of a number of pointed inwardly-projecting members *a'*.

Having thus described my invention, what 25 I claim as new, and desire to secure by Letters Patent, is—

The design for a watch-charm and cigar-cutter, as herein shown and described.

In testimony whereof I have signed my 30 name to this specification in the presence of two subscribing witnesses.

JOHN F. RAWLINGS.

Witnesses:

M. DOWNING,
J. B. LESTER.
